UNITED STATES PATENT OFFICE.

HENRY W. GAINES, OF BOWLING GREEN, KENTUCKY.

CLAMP FOR WIRE FENCES.

1,073,228.

Specification of Letters Patent. Patented Sept. 16, 1913.

Application filed September 14, 1912. Serial No. 720,369.

To all whom it may concern:

Be it known that I, HENRY W. GAINES, a citizen of the United States, residing at Bowling Green, in the county of Warren and State of Kentucky, have invented certain new and useful Improvements in Clamps for Wire Fences, of which the following is a specification, reference being had therein to the accompanying drawing.

10 This invention relates to clamping devices and has special reference to a device for clamping the wires of a wire fence so that the fence may be stretched as is common in erecting such fences.

15 The principal object of the invention is to improve and simplify the general construction of devices of this character.

A second object of the invention is to provide a novel form of gripping means for 20 use in connection with such a clamp.

With the above and other objects in view, this invention consists in general of novel constructions, combinations and arrangements of parts, as will be hereinafter fully 25 described, illustrated in the accompanying drawings, and specifically claimed.

In the accompanying drawings, like characters of reference indicate like parts in the several views, and: Figure 1 is a side elevation showing the clamp applied to a fence. Fig. 2 is a front elevation with the draft means removed. Fig. 3 is a face view of the inside of one of the clamping members. Fig. 4 is a horizontal section showing the 30 manner in which the fence wire is engaged. Fig. 5 is a view of one of the draft hooks. Fig. 6 is a cross section of the binding nut carried by the upper ends of the clamps.

In carrying out the objects of this invention there is provided a pair of clamp members 20 and 21 which are preferably constructed of wood, and these members have their upper ends beveled as at 22. The member 20 has its lower end provided with 45 an angle plate 23 which has an opening 24 therein, while the member 21 has its lower end provided with a plate 25 which has an angularly disposed extremity 26 adapted to pass through the opening 24. On the member 20 are spaced U-shaped bands 27 having outwardly turned extremities 28 on the legs, and these extremities are inclined as can readily be seen by reference to Fig. 2. The member 21 is provided with similar U-shaped bands 29, the legs whereof have offset extremities 30 provided with diagonal

faces 31 which engage over the extremities 28 when the parts are locked in position. On the member 20 at its upper end is provided a cap 32 wherefrom extends a bolt 33, the bolt being at right angles to the beveled face 22 of said member. Upon the member 21 at its upper end is secured an angle plate 34 having a slotted extremity 35 arranged to engage the bolt 33. Mounted on the bolt 33 is a nut 34' which is provided with lateral extensions 35'. This nut fits in an opening 36 formed in a plate 37 having upturned handle ends 38. On the inner face of each member is one or more crimping 70 wires 39, while the opposed member is provided with suitable grooves 40 so that when the two members are together, the crimping wires on one will register with the grooves on the other. These crimping wires have 75 their extremities turned in and embedded as at 41.

The draft rigging consists of a draft bar or spacer bar 42 under which are attached draft chains 43 meeting in the ring 44. 80 These chains are prolonged at the opposite extremities and connect by means of rings 45 with the rectangular hooks 46 adapted to engage the clamp. The fence is indicated at 47, and it will be seen by reference to the 85 figures that the members 20 and 21 lie on opposite sides of the line wires of the fence. Now when these members are thus positioned and the bands and other portions of the separate members engaged, the handles 90 38 may be grasped and the nut rotated so as to force the member 22 downward and in the direction of the member 23, this action being caused by the peculiar disposition of the engaging parts. Thus the wires may be 95 clamped, and heavy draft may be applied thereto without any chance of these wires slipping.

There has thus been provided a simple and efficient device of the character described, and for the purpose specified.

Having thus described the invention, what is claimed as new, is:—

1. In a device of the kind described, a pair of clamping members, U-shaped straps 105 carried by one of said members, provided with outwardly turned inclined extremities, other U-shaped straps carried by the remaining member provided with lateral extremities having inclined faces, the inclined 110 faces of one member engaging the outwardly turned ends of the other, an inclined bolt

carried by one of said members, an inclined plate carried by the other member through which said bolt passes, and a nut on said bolt.

- 5 2. In a device of the kind described, a pair of clamping members, U-shaped straps carried by one of said members provided with outwardly turned inclined extremities, other U-shaped straps carried by the remaining member provided with lateral extremities having inclined faces, the inclined faces of one member engaging the outwardly turned ends of the other, an inclined bolt carried by one of said members, an inclined plate carried by the other member through which said bolt passes, a foot plate carried by one of said members and extending beneath the other and provided with an opening adjacent its end, and an inclined plate carried by the other member having an extremity arranged to pass through said opening.
- 10 3. In a device of the kind described, a pair of clamping members, U-shaped straps carried by one of said members provided with outwardly turned inclined extremities,
- 15
- 20
- 25

other U-shaped straps carried by the remaining member provided with lateral extremities having inclined faces, the inclined faces of one member engaging the outwardly turned ends of the other, an inclined bolt carried by one of said members, a nut positioned upon one of said members, an inclined plate carried by the other member through which said bolt passes, a foot plate carried by one of said members and extending beneath the other and provided with an opening adjacent its end, an inclined plate carried by the other member having an extremity arranged to pass through said opening, lateral extensions on said nut, a plate having an opening therein to receive said nut and having said lateral extensions secured thereto, and upturned handles on said plate.

In testimony whereof I hereunto affix my signature in presence of two witnesses.

HENRY W. GAINES.
